UNITED STATES PATENT OFFICE.

ADAM M. SMITH, OF MILWAUKEE, WISCONSIN, ASSIGNOR OF ONE-HALF TO ATLAS METAL PARTS COMPANY, OF MILWAUKEE, WISCONSIN, A CORPORATION OF WISCONSIN.

SPINNING-TOP.

1,355,514.

Specification of Letters Patent. Patented Oct. 12, 1920.

Application filed April 30, 1919. Serial No. 298,749.

To all whom it may concern:

Be it known that I, ADAM M. SMITH, a citizen of the United States, residing at Milwaukee, county of Milwaukee, and State 5 of Wisconsin, have invented new and useful Improvements in Spinning-Tops, of which the following is a specification.

My invention relates to improvements in spinning tops of that type in which the rotary motion of the body of the top is derived from a separable spindle rotating about a vertical axis.

The object of my invention is to provide a simple and durable top and actuating 10 mechanism therefor which can be made at minimum cost, and operated without difficulty by any child. A further object of my invention is to provide a form of top which can be advantageously used for advertising 15 purposes.

In the drawing:—

Figure 1 is a plan view of my improved top.

Fig. 2 is a side elevation of the same, 20 partly in central vertical section, and showing the spinning mechanism in elevation, and in engagement with the top for a spinning operation, with dotted lines illustrating the actuating mechanism in raised position.

Fig. 3 is a sectional view on line 3—3 of Fig. 2.

Like parts are identified by the same reference characters throughout the several 25 views.

The body of the top comprises a flat disk 1, having a bowl shaped central depression 2, from the upper surface of which rounded studs 3 project at equal distances from the central axis, these studs being preferably formed by indenting the bowl shaped portion from the underside. At the center of the depression 2, the surface is downwardly indented to form a corresponding projection 4 on the underside, which serves as the spinning point upon which the top revolves. The margin of the disk 1 is preferably folded downwardly and inwardly upon itself, forming a marginal bead 5. The upper surface of the top between this bead 5 and the central bowl shaped depression may be printed or stamped with suitable advertising matter, the surface, how-

ever, being preferably smooth in order that minimum air resistance may be encountered.

The spinning tool or mechanism comprises a bar of flat wire, twisted to form a helical screw 7, the thread of which is steeply pitched along the longitudinal axis of the bar. The lower portion of the bar is provided with an untwisted shank 8, below which the bar is looped to form an oval shaped eye 9, the lower side of which is curved in an arc substantially corresponding to the curvature of the bowl shaped depression 2 of the top.

A sleeve 10 is adapted to slide along the screw 7, and is provided with an inwardly extending screw actuating projection 11, which is loosely entered in the screw channel, and is adapted to follow the channel from the top to the bottom of the screw when the sleeve is reciprocating thereon.

The sleeve may be conveniently formed of a piece of wire wound in a close helical coil with successive turns in contact, and with the lower extremity inturned to engage in the screw channel or groove, and constituting the screw actuating projection 11. The extremity of the wire forming this projection is preferably so disposed that it will be in approximate contact with the screw thread on one side thereof, whereby this extremity may bear upon the thread with little frictional contact when the sleeve is reciprocated.

The sleeve 10 constitutes the handle of the tool. When this sleeve is supported in a vertical position with the screw suspended therefrom, the latter will descend by gravity until the sleeve engages the elbowed upper extremity 12 of the screw bar. Thereupon, if the eye 9 is placed in the bowl shaped depression 2 of the spinning body, with the screw in a vertical position, and the disk 1 in a horizontal position, a downward pressure upon the sleeve will cause the screw to turn, and its motion will be transmitted to the body. The stud projections 3 prevent the eye 9 from rotating in frictional contact with the upper surface of the depression 2 if the friction should not be sufficient to transmit motion from the eye to the body.

As soon as the sleeve has been moved 105 downwardly to the lower end of the screw,

or to any other intermediate point at which it is desired to release the body, and allow it to spin free, the sleeve is lifted quickly, thereby withdrawing the eye 9 from contact 5 with the body, and allowing the latter to continue to spin under the momentum which it has acquired. Thereafter, the momentum 10 of the body may be increased by a succession of quick blows delivered downwardly in the central depression 2, by means of the eye 9, the operator maintaining his grasp upon the sleeve 10, and lifting the tool from the body 15 instantly as soon as the downward pressure upon the sleeve ceases, and preferably before the sleeve reaches the lower end of the screw.

During each upward movement of the sleeve, the screw will rotate by gravity in the reverse direction, thus passing downwardly 20 through the sleeve to a point where the spinning impulse can be effectively delivered by a quick downward thrust. It will also be found that inasmuch as the screw is rigidly connected with the eye by means of 25 the shank 8, a quick upward movement of the sleeve will be effective to withdraw the actuating eye 9 from the depression 2 at the instant that the sleeve is lifted. This is of considerable importance, since it relieves the 30 body from the detaining effect which would result if even a portion of the weight of the eye shank and screw were to be sustained by the body during the initial retractive movement, with resulting frictional contact. The 35 reverse movement of the screw while the sleeve is being lifted is not sufficiently rapid to prevent a complete withdrawal of the eye from the bowl shaped depression.

I claim:—

40 1. A spinning top comprising the combination with a disk having a central bowl shaped depression, a screw having an eye at its lower end, the lower surface of which is curved in substantial conformity to the curvature of 45 said depression, a sleeve through which the screw passes, and an actuating projection carried by the sleeve, and adapted to engage between the screw threads.

50 2. A spinning top comprising the combination of a disk shaped body, having a bowl shaped depression indented at the center of the body to form a downwardly projecting spinning point, a body actuating mechanism comprising a piece of flat wire

twisted to form a screw, and looped at its 55 lower end to form an eye, and an actuating handle having a cylindrical cavity through which the screw passes, and provided with a projection to loosely engage the screw, said handle when reciprocated being adapted to 60 rotate the screw upon its own axis.

3. A spinning top comprising the combination of a disk shaped body, having a bowl shaped depression indented at the center of the body to form a downwardly projecting spinning point, a body actuating mechanism comprising a piece of flat wire 65 twisted to form a screw, and looped at its lower end to form an eye, and an actuating handle having a cylindrical cavity through 70 which the screw passes, and provided with a projection to loosely engage the screw, said handle when reciprocated being adapted to rotate the screw upon its own axis, and said eye being adapted, when fitted to the bowl 75 shaped projection in the body, to center itself therein, and transmit rotative motion to the body by frictional contact with the surface of said depression.

4. A spinning top comprising the combination of a disk shaped body, having a bowl shaped depression indented at the center of the body to form a downwardly projecting spinning point, a body actuating mechanism comprising a piece of flat wire 85 twisted to form a screw, and looped at its lower end to form an eye, and an actuating handle having a cylindrical cavity through 90 which the screw passes, and provided with a projection to loosely engage the screw, said handle when reciprocated being adapted to rotate the screw upon its own axis, and said eye being adapted, when fitted to the bowl shaped projection in the body, to center 95 itself therein, and transmit rotative motion to the body by frictional contact with the surface of said depression, the walls of said depression being also provided with upwardly extending projections in a position to be engaged by said eye when the latter slips along the surface of the body.

In testimony whereof I affix my signature in the presence of two witnesses.

ADAM M. SMITH.
